UNITED STATES PATENT OFFICE.

EDWARD F. BRIGHAM AND JAMES N. DANIELS, OF NEWARK, NEW JERSEY, ASSIGNEES TO BENJAMIN & JOHNS, A CORPORATION OF NEW JERSEY.

AUTOMATIC WORK-FEED CONTROL FOR SEWING MACHINES.

Application filed September 8, 1923. Serial No. 661,562.

To all whom it may concern:

Be it known that we, EDWARD F. BRIGHAM and JAMES N. DANIELS, both citizens of the United States, and residents of Newark, in the county of Essex and State of New Jersey, have invented new and useful Improvements in Automatic Work-Fee Control for Sewing Machines, of which the following is a specification.

10 The primary objects of the invention are to provide a novel machine for sewing impenetrable objects such as metal fasteners, or objects which it is desired not to pierce with the needle, on garments or other material,

15 for instance, brassières and under bodices, or stitching an article having an impenetrable object therein, or producing a continuous line of stitches of different lengths, and more particularly to provide such a machine for sewing wire eyelets into the edge seam of garments or on strips of cloth which are adapted to be secured to the edge of an opening in the garment to operate with hooks on the opposite edge.

20 In the manufacture of certain classes of garments it is customary to arrange a plurality of metal eyelets in spaced relation in a row on the opening edges of a garment in a pocket or fold formed with openings through which the eyes of eyelets project, or on strips of cloth to be secured to said edges, and then sew said eyelets on the garment or strips by a line of stitching at the edge of said fold or pocket with the well-known type of sewing machine. In such an operation the needle of the sewing machine is frequently broken by striking an eyelet and thus the sewing operation is retarded and time and needles are wasted.

25 Another object is to provide a device of the character described controlled by the work for automatically regulating the work feed mechanism of a sewing machine to vary the length of the stitches made by the machine.

30 Other objects of the invention are to provide a machine for sewing eyelets or other impenetrable objects on a piece of cloth or the like including means actuated by the eyelet or impenetrable object to automatically regulate the work feed mechanism of the machine whereby the movement of work

35 is accelerated when the eyelet or impenetrable object is passing beneath the needle to produce a long stitch over the eyelet or object and prevent the needle from engaging the same; to thus provide a trip mechanism to be actuated by the work and means controlled by said trip mechanism to regulate the work feed mechanism; to provide a work feed regulating device of the character described which may be applied to any known type of sewing machine, and to obtain other results and advantages as may be brought out by the following description.

40 Referring to the accompanying drawings, in which like numerals of reference indicate the same parts throughout the several views,

45 Figure 1 is a side elevation of a sewing machine embodying our invention with the parts shown in solid lines to permit normal feed of the work by the machine;

50 Figure 2 is an end elevation of the standard end of the machine with the driving wheel removed;

55 Figure 3 is a perspective diagrammatic illustration of the automatic work feed control mechanism;

60 Figures 4 and 5 are enlarged fragmentary side elevation and sectional views showing the work feed operating lever and the means for regulating the speed of the work feed thereby;

65 Figure 6 is a fragmentary end elevation of the head end of the machine showing the trip mechanism to be actuated by the work;

70 Figure 7 is a horizontal sectional view taken on the line 7—7 of Fig. 6;

75 Figure 8 is a top plan view of the electric switch mechanism, and

80 Figure 9 is a transverse sectional view taken on the line 9—9 of Fig. 6.

85 For the purpose of illustrating the principles of the invention, we have shown the same in connection with a known type of sewing machine, the parts of said machine unnecessary for a complete understanding of our invention being omitted for the sake of clearness. The said machine includes a standard A carrying at one end the head B in which is vertically reciprocable the needle bar C driven from the usual drive mechanism. The said head also has mounted therein the usual presser foot bar E

carrying at its lower end a presser foot F adapted to engage the work and hold the same against the feed mechanism G mounted in the bed H of the machine.

- 5 We have also shown the invention in connection with sewing a known type of fastener strip to the edge of a garment, such as a brassière, the said fastener strip comprising a base strip a and a binding strip b between which are secured wire eyelets c which project beyond the edges of the base strip as shown in Figures 6 and 7 to cooperate with hooks carried by the opposite edge of the garment. These fastener strips 10 are sewed to the edge of the garment d by means of a line of stitching adjacent the edge of the garment and overlying the eyelets c. One object of our invention is to provide a machine for producing such a 15 line of stitching e (see Fig. 7) without danger of breaking the needle or the thread by contact of the needle with the eyelets, and at the same time forming one or more stitches between the arms of the eyelets 20 whereby the connection of the eyelets to the garment is materially strengthened.
- The invention may be embodied in any suitable work feed mechanism per se, but for simplicity of description and for the 25 purpose of illustrating one preferred embodiment of the invention, we have shown the same utilized in connection with a known type of work feed mechanism. This mechanism includes the usual drive shaft I 30 which is journaled in the standard of the machine and carries at one end a fly wheel J and drive pulley K adapted to be driven by a belt from any suitable source of power. Within the standard A of the machine the 35 drive shaft is provided with a crank L on which is mounted a bearing block M having diametrically opposite flat bearing surfaces N to receive the inner faces of the arms O of the bifurcated end of an actuating lever 40 P. The other end of said lever is pivotally connected at Q to a crank arm R carried by a shaft S journaled in and extending longitudinally of the bed H of the machine. The said shaft S is also connected by a 45 second crank T to a feed block U which is in turn connected to a crank arm V carried by a second shaft W arranged parallel to the shaft S and oscillated from the drive shaft I by the usual mechanism (not shown). In the operation of the machine the shafts S and W are constantly oscillated, the shaft S serving to move the feed block U longitudinally and the shaft W serving simultaneously to raise the feed 50 block through the throat plate X arranged in the bed of the machine beneath the needle and presser foot. The distance of longitudinal movement of the feed block U is adjusted by varying the leverage of the lever P, so that the speed of movement of the

work through the machine is correspondingly varied. For this purpose the lever P is pivotally connected intermediate its ends at Y to one end of a link Z, the other end of which is pivotally connected to one arm 70 of a bell crank AA pivotally connected at BB to the standard of the machine. The other arm of said bell crank lever AA projects through a slot CC at the front of the standard of the machine. Thus, by oscillation of the bell crank lever AA by means of the arm thereof projecting through the slot CC, the pivot Y of the lever P is moved toward or away from the crank L to vary the leverage whereby the extent of oscillation of the shaft S is correspondingly varied. In the drawings, when the projecting arm of the bell crank lever is at the lower end of the slot CC the feed block U is moved the maximum distance, while when the projecting arm of the bell crank lever is at the upper end of the slot CC the feed block is moved the minimum distance.

In accordance with this form of the invention the relation of the pivot Y to the crank L and thus the extent of movement of the feed block U, is automatically regulated by the work passing beneath the needle and moved by the feed block. In the present instance, as above described, the work constitutes the edge of a garment to which a fastener strip carrying metal loop eyelets is to be sewed. For this purpose, we have shown the projecting arm of the bell crank lever AA connected to one end of a link 1 which is disposed vertically on the standard A and is longitudinally reciprocable through a bearing bracket 2 rigidly secured to the standard A in any suitable manner. The link 1 is normally influenced upwardly to move the projecting arm of the bell crank lever AA to the upper end of the slot by means of a tension spring 3 connected between the bell crank lever and the bearing bracket 2. In this manner the bell crank lever AA is normally influenced into the position to produce a minimum movement of the feed block U. An adjusting nut 4 is threaded on the link 1 beneath the bearing bracket 2 for the purpose of limiting the upward movement of the link and thereby normally maintain regular uniform movement of the feed block U and thus regular stitches of uniform length. A jam nut 5 is also provided for holding the adjusting nut 4 in adjusted position, and a buffer washer 6 is interposed between the adjusting nut and the bearing bracket to reduce noise and shock incident to reciprocation of the link 1.

The upper end of the link 1 carries a cap nut 7 which is adapted to frictionally engage one end of a lever 8 pivotally mounted intermediate its ends at 9 on a bracket 10. The other end of said lever 8 is adapted

to frictionally engage a cap nut 11 carried by one end of a core 12 mounted in an electromagnetic coil 13 which is secured by a bracket 14 to the standard of the machine 5 with the core in substantially vertical position. The bracket 10 may be conveniently mounted on the bracket 14, as shown. When the coil 13 is energized the core 12 is moved upwardly and such movement of the core 10 oscillates the lever 8 to move the link 1 downwardly and thereby adjust the work feed mechanism to produce a larger movement of the feed block than the normal movement determined by the adjusting nut 4. When 15 the coil 13 is deenergized the core moves downward by gravity and under the influence of spring 3 through the lever 8, such downward movement of the core 12 being limited by an adjusting nut 15 between 20 which and the bracket 14 is arranged a buffer washer 16.

The coil 13 is connected in circuit with a source of electricity and a switch controlled by a trip mechanism actuated by the work, 25 in the present instance by engagement with the eyelets or other objects on the material being sewed. The said trip mechanism comprises a sleeve 17 slidably mounted on the presser foot bar E and held against rotation by a set screw 18. The said sleeve is provided with an arm 19 on which is adjustably mounted by means of set screws 20 a bracket 21 carrying at one end a roller 22 adapted to engage the work. The sleeve 30 17 is normally influenced toward the work by means of a compression spring 23, said movement of the sleeve being limited by the roller 22. The arm 19 is provided with a lateral extension 24 on which is pivotally mounted a bell crank lever 25 one end of which is provided with a trip finger 26 adapted to engage the work while the other end carries a switch blade 27 adapted to close the circuit through switch plates 28 and 29 connected in circuit with a source 40 of electricity and the electromagnet 13. The switch blade 27 is normally held out of engagement with the switch plates 28 and 29 and the trip finger 26 is normally held in engagement with the work, by means of a spring 49. It will be observed that the roller 22 ensures that the trip finger 26 will always be so positioned as to maintain the switch 45 normally open and will permit the presser foot F to descend to the work and accommodate irregularities in the thickness thereof without affecting the operation of the trip finger 26.

The lateral extension 24 of the arm 19 is 50 preferably slotted as at 50 to receive the pivot 51 of the bell crank lever 25 so that the said pivot may be adjusted relatively to the presser foot to produce proper relation of the trip finger 26 and the needle N¹. In 55 the present instance opposite sides of the

slot 50 are convergently beveled and a block 53 is mounted therein carrying a threaded stud 54 which pivotally receives the bell crank lever 25, the bell crank lever being held on said stud and the block 53 being held 70 against movement in the slot by means of a cap 55 threaded on the stud 54.

The switch mechanism may be of any desired construction, but in the present instance, is shown as comprising a block 56 75 of insulation secured to the head of the machine and having the contact plates 28 and 29 mounted thereon in insulated relation by means of screw 57.

In the operation of the machine the work 80 is fed beneath the presser foot by the work feed mechanism of the machine and the needle bar is reciprocated by the usual drive mechanism. The trip finger 26 is so positioned as to be engaged by the eyelets 85 or other object on the work it is desired not to pierce with the needle, and as the work is fed beneath the presser foot, the eyelets or other objects will be drawn beneath the trip finger 26, as shown in Figures 6 90 and 7. The trip finger is thus raised so as to oscillate the bell crank lever and close the circuit through the electromagnet 13, whereupon the said magnet is energized and causes reciprocation of the core 12 upwardly 95 to oscillate the lever 8. The oscillation of said lever 8 forces the link 1 downwardly to adjust the position of the pivot Y of the lever P relative to the crank L as above described. Movement of the link 1 downwardly is limited by means of an adjusting nut 30 adapted to engage the top of the bearing bracket 2. Obviously, by varying the position of the adjusting nut 30 on the link 1 the extent of movement of the bell 100 crank lever AA can be regulated to provide for a movement of the feed block U the desired extent. When the link 1 is forced downwardly as above described the feed block U is caused to move a greater extent 105 than the movement determined by the adjusting nut 4 so that the speed of movement of the work beneath the needle of the machine is accelerated while each arm of the eyelet is passing beneath the needle. Thus 110 the arm of the eyelet is moved from beneath the needle before the latter descends, thereby preventing the possibility of engagement of the needle with the eyelet. A longer stitch than the regular stitches is 115 thereby produced over the arm of the eyelet. It will be observed that the acceleration of the feed of the work is controlled by 120 the trip mechanism which is in turn actuated by the eyelet or other object on the work, and that after an eyelet has passed from beneath the trip finger 26 the machine assumes the normal rate of work feed due to the return of the work feed mechanism to its normal position by the spring 3. It 125

will further be noted that the needle will descend between the arms of the eyelets and form a regular stitch, so that the connection of the eyelets to the material is greatly strengthened. The cap nuts 7 and 11 may be utilized for taking up lost motion between the lever 8, the core 12 and the link 1.

The invention is clearly susceptible for use in producing a continuous line of 10 stitches of different lengths and is not limited in its application to use with work carrying eyelets or other impenetrable objects as hereinbefore described. Any suitable means might be utilized for controlling 15 energization of the coil 12 at predetermined intervals in place of the trip mechanism herein described, for the purpose of accelerating the speed of movement of the work feed mechanism at predetermined intervals 20 of time to produce stitches of different lengths.

While we have shown and described our invention embodying certain details of construction and used in one way, it will be 25 understood that this is only for the purpose of illustrating the principles of the invention and that the invention is susceptible of execution by means of many different mechanisms and details of construction and 30 may be adapted for many other uses without departing from the spirit or scope of the invention. Therefore, we do not wish to be understood as limiting ourselves, except as required by the following claims 35 when construed in the light of the prior art.

Having thus described the invention, what we claim is:

1. In a sewing machine, stitch-forming mechanism including a needle, means for 40 actuating the same, and work-feeding means, the movements of said work-feeding means and said needle having a normal definite relation, means for varying the movements of said work-feeding means independently of 45 the movements of said needle, electromagnetic means for operating the last-mentioned means, and electric switch mechanism actuated by variations in the work surface for controlling said electromagnetic means.

50 2. In a sewing machine, stitch-forming mechanism including a needle, means for actuating the same, and work-feeding means, the movements of said work-feeding means and said needle having a normal definite 55 relation, means for varying the movements of said work-feeding means independently of the movements of said needle, and means constantly in engagement with the work and actuated by variations in the work 60 surface, for controlling the last-mentioned means.

3. In a sewing machine, stitch-forming mechanism including a needle, means for 65 actuating the same, and work-feeding means, the movements of said work-feeding means

and said needle having a normal definite relation, means for varying the movements of said work-feeding means independently of the movements of said needle, power means for operating the last-mentioned means, and 70 means actuated by variations in the work surface for controlling said power means.

4. A machine of the character described including a needle, means for actuating the same, means for feeding work through said 75 machine to be operated upon by said needle, the movements of said work feeding means and said needle having a normal definite relation, and means controlled by the work for automatically varying the movement of 80 said work feeding means.

5. A sewing machine for operating on work having projections thereon, including a needle, means for actuating the same, means for feeding said work through said 85 machine, and means controlled by engagement with said projections on said work for automatically varying the movement of said work-feeding means.

6. A sewing machine for operating upon 90 work having an object to be sewed thereon, including a needle, means for actuating the same, means for feeding said work through said machine, and means controlled by engagement with said object for varying the 95 actuation of said work-feeding means to vary the speed of movement of the work and prevent contact of said needle with said object.

7. A sewing machine for operating on 100 work having a wire loop eyelet thereon, including a needle, means for actuating the same, means for feeding said work through said machine, and means controlled by engagement with said eyelet for automatically 105 varying the actuation of said work-feeding means to vary the speed of movement of the work to prevent contact of said needle with the arms of said eyelet and permit said needle to form a stitch between the 110 arms of the eyelet.

8. A machine of the character described including a work feed mechanism, means for actuating the same, means for varying the actuation of said mechanism by said 115 actuating means, and automatic means controlled by the work for actuating said varying means at predetermined intervals.

9. In a sewing machine for operating upon work having projections thereon, the combination of a work feed mechanism, means for actuating the same, means for varying the actuation of said mechanism by said actuating means, and means automatically controlled by engagement with 125 said projections on the work for actuating said means for varying said work feed mechanism actuating means.

10. In a sewing machine for operating upon work having projections thereon, the 130

combination of a work feed mechanism, means for actuating the same, means for varying the actuation of said mechanism by said actuating means, and trip mechanism 5 adapted to be engaged by said projections as the work is fed through the machine for automatically controlling actuation of said means for varying the actuation of said work feed mechanism.

10 11. In a sewing machine for operating upon work having projections thereon, the combination of a work feed mechanism, means for actuating the same, means for varying the actuation of said mechanism by 15 said actuating means, means actuated by power independent of said machine actuating means for operating said means for varying the actuation of said work feed mechanism, and means actuated by engagement 20 with said projections for controlling said last-mentioned means.

12. In a sewing machine of the character described, the combination of a work feed mechanism, means for actuating the same, 25 means for varying the actuation of said work feed mechanism by said actuating means, electromagnetic means for operating said varying means, and means for automatically controlling operation of said 30 electromagnetic means.

13. In a sewing machine of the character described, the combination of a work feed mechanism, means for actuating the same, means for varying the actuation of said 35 work feed mechanism by said actuating means, electromagnetic means for operating said varying means, and means for automatically controlling operation of said electromagnetic means at predetermined 40 intervals.

14. In a sewing machine of the character described, the combination of a work feed mechanism, means for actuating the same, means for varying the actuation of said 45 work feed mechanism by said actuating means, electromagnetic means for operating said varying means, and electric switch means actuated by work passing through the machine for automatically controlling 50 operation of said electromagnetic means.

15. In a sewing machine of the character described, the combination of a work feed mechanism, means for actuating the same, electromagnetic means for varying the 55 actuation of said work feed mechanism, and means for automatically controlling operation of said electromagnetic means.

16. In a sewing machine of the character described, the combination of a work feed mechanism, means for actuating the same, means for varying the actuation of said work feed mechanism by said actuating means, an electromagnet, an operative connection between said electromagnet and said 60 varying means, a source of electricity con-

nected to said electromagnet, and an automatically actuated electric switch for controlling the operation of said electromagnet by said source of electricity.

17. In a sewing machine for operating on work having projections thereon, the combination of a work feed mechanism, means for actuating the same, electromagnetic means for varying the actuation of said feed mechanism, and electric switch mechanism 70 actuated by engagement with said projections on the work as the work passes through the machine for controlling operation of said electromagnetic means.

18. In a machine of the character described for operating upon work having a plurality of spaced projections thereon, the combination of a stitch producing mechanism having a reciprocating needle, means for feeding said work beneath said needle 75 normally at a uniform speed, and means controlled by engagement with said projection on the work for automatically accelerating the speed of movement of said work when one of said projections is passing 80 beneath said needle.

19. In a sewing machine for operating upon work having wire loop eyelets thereon, a stitch-forming mechanism including a needle, means for actuating the needle, and means for feeding the work beneath the needle normally at a uniform speed, means for accelerating the speed of movement of the work, and means to be engaged by said eyelets as the latter approach the path of 95 the needle to control the last-mentioned means whereby the movement of the work is accelerated while an eyelet is passing beneath the needle to prevent contact of the needle with said eyelets.

20. In a sewing machine for operating upon work having wire loop eyelets thereon, a stitch-forming mechanism including a needle, means for actuating the needle, and means for feeding the work beneath the 100 needle normally at uniform speed, means for accelerating the speed of movement of the work, a trip mechanism for controlling the last-mentioned means and including a trip finger in the path of and to be actuated by said eyelets, said trip finger being of a size to enter between the arms of each of said eyelets, whereby the movement of the work is temporarily accelerated as an arm of an eyelet passes beneath the needle and again retarded to normal speed to permit at least one stitch to be formed between the arms of each eyelet.

21. The combination with a sewing machine including a needle, means for actuating the needle, work-feeding means, and means for varying movement of said work-feeding means, of a power operated means connected to said work-feed varying means to actuate the same for varying the speed 125 130

of movement of the work, and means actuated by variations in the work surface for automatically controlling said power means.

22. The combination with a sewing machine including a frame, a needle, means for actuating the needle, work-feeding means, and means for varying movement of said work-feeding means, of an electromagnetic means mounted on said frame, an operative connection between said electromagnetic means and said work-feed varying means, and electric switch mechanism actuated by variations in the work surface for controlling said electromagnetic means.

23. The combination with a sewing machine including a drive shaft, a needle, work-feed means, an operative connection between said needle and said drive shaft, and an operative connection between said drive shaft and said work-feed means including a lever connected between said shaft and the work-feed means and pivoted intermediate its ends on a bell-crank lever so that pivotal movement of said bell-crank lever varies the speed of movement of the

work, of power means operatively connected to said bell-crank lever to oscillate the same, and means for controlling said power means.

24. The combination set forth in claim 25 in which the last-mentioned means is actuated by variations in the work surface.

25. The combination with a sewing machine including a drive shaft, a needle, work-feed means, an operative connection between said needle and said drive shaft, and an operative connection between said drive shaft and said work-feed means including a lever connected between said shaft and the work-feed means and pivoted intermediate its ends on a bell-crank lever so that pivotal movement of said bell-crank lever varies the speed of movement of the work, of power means operatively connected to said bell-crank lever to oscillate the same, and means for causing pivotal movement of said bell-crank lever by said power means.

EDWARD F. BRIGHAM.
JAMES N. DANIELS.
